10

The present invention relates to monoazo dyes which develop brown shades upon subsequent chromation, more particularly by the dyeing and chromation of wool and polyamide fibers in a single neutral or slightly acid bath according to the "metachrome" process.

These dyes have the general formula:

wherein X is selected from halogen atoms, and NO₂ groups;

Y is selected from acylamino groups, halogen-containing acylamino groups and alkoxy carboxyamino groups.

"Metachrome" brown shades have generally been heretofore obtained by the metallization on fibers, of mono-azodyes which are the product obtained by coupling the diazo compounds of suitable orthoaminophenols with para-alkyl phenol derivatives, (e.g., para-cresol, para-tertiary butylphenol, p-tert.amyl phenol, etc., and preferably also with other substitutions, such as, e.g., 1-hydroxy-2-acetamino-4-methyl benzene, 1-hydroxy-2-propionyl amino-4-tertiary-butyl benzene, 1-hydroxy-2-acetamino-4-tert.amyl benzene, etc.).

Although a certain number of the aforementioned dyes are known from the literature to have valuable dyeing properties, their preparation presents considerable difficulties due to the poor coupling tendency of diazotized ortho-aminophenols and the para-alkyl phenols. Moreover, when these phenols are substituted with alkyl chains higher than ethyl, their solubility in alkaline water is very slight.

When 2-hydroxy-naphthalene is used as the coupling agent, although the coupling is facilitated, the shade of the final dye is in the area of violet and the dyes therefore cannot be used as brown.

It has now been surprisingly found that by using 2-hydroxy-5,6,7,8-tetrahydronaphthalene as the coupling agent for dyes to be metallized on the fiber, decidedly brown shades are obtained after metallization and, at the same time, the coupling reaction is remarkably facilitated.

An object of the present invention is therefore to provide monoazo dyes, for wool and polyamidic fibers, which are metallizable on the fibers during or after dyeing and have the general formula:

2

wherein X and Y have the meaning given above.

Another object of the present invention is to provide textile materials such as fibers, yarns and the like, which are dyed with the instant dyes.

Other objects and advantages of the present invention, will become apparent hereinafter.

These dyes are obtained, according to the present invention, by diazotizing and coupling, in any conventional suitable manner, a compound of the formula:

in which X and Y have the aforementioned meaning, with 2-hydroxy-5,6,7,8-tetrahydronaphthalene.

The new dyes, obtained according to the present invention, are excellent for wool and polyamidic fibers and are suitable for a dyeing step followed by a chromation treatment. Preferably, the dyeing and chromation can be carried out in a single bath, which is either neutral or slightly acid, according to the so called "metachrome" process.

By employing the dyes of general Formula 1, it is surprisingly simple, as is illustrated below, to obtain (after metallization) brown shades which heretofore could be obtained only with certain difficulties in preparation.

The dyes of the present invention possess further advantages. Thus, they possess good fastness to light even under wet conditions and also good fastness to "potting" treatments, even in comparison with dyes derived from alkylphenols having a higher molecular weight (e.g., p.tert.butyl, p-tertiary amyl) and even in comparison with dyes possessing further substituents such as 1-hydroxy-2-acetamino-4-methylbenzene and 1-hydroxy-2-acetamino-4-tert.butylbenzene. This improved fastness of the present dyes is probably due to the cyclic structure of the alkyl substitution.

Among the numerous 2-aminophenol derivatives which can be used according to the present invention, there can be mentioned as examples:

- 45 1-hydroxy-2-amino-4-nitro-6-formyl-amino-benzene,
- 1-hydroxy-2-amino-4-nitro-6-acetamino-benzene,
- 1-hydroxy-2-amino-4-nitro-6-chloro-acetamino-benzene,
- 1-hydroxy-2-amino-4-chloro-6-acetamino-benzene,
- 1-hydroxy-2-amino-4-nitro-6-propionylamino-benzene,
- 1-hydroxy-2-amino-4-chloro-6-propionylamino-benzene, and
- 1-hydroxy-2-amino-4-nitro-6-methoxycarboxyl-amino-benzene.

The dyeing step may be carried out using any suitable conventional procedure. The present invention is described with reference to some of its preferred embodiments. There are, however, obviously many modifications and variations of the instant invention which will be evident to persons skilled in the art. For example, various phenols may be employed as the o-aminophenol, which is coupled with 2-hydroxy-5,6,7,8-tetrahydronaphthalene in order to obtain a dye to be metallized with a brown shade. It is to be understood that these and other suitable modifications and variations are within the spirit and scope of the present invention.

The invention is illustrated but not limited by the following examples in which all parts are by weight unless otherwise stated, and the relation between parts by weight and parts by volume is that of grams to millimeters.

Example 1

(1) 21.1 parts of 1-hydroxy-2-amino-4-nitro-6-acetamino-

benzene are diazotized at 5-10° C., preferably in the presence of 0.1-1 part of Dispersol CV (alkylphenol-ethyleneoxide condensation product), 25 parts of water, 22 parts of 30% HCl and 25 parts by volume of a 4 N sodium nitrite solution, with the addition of 30 parts of ice, and by using outside cooling.

The suspension of diazo-compound is neutralized with sodium carbonate and is introduced at 0° C. into a solution of 14.9 parts of 2-hydroxy-5,6,7,8-tetrahydronaphthalene in 100 parts of water containing 4 parts of sodium hydroxide and 17 parts of sodium carbonate.

When the coupling is ended, the precipitated dye is separated by filtration and is suspended in water slightly alkalinized with sodium carbonate. It is then filtered and dried.

The monoazodye thus obtained has the following formula:

The dye is a black-brown powder, which is very suitable for dyeing wool by the known metachrome process, thus giving a dark-brown shade with very good wet and light fastness.

The dyeing can also be carried out by employing successive chromation.

Example 2

22.5 parts of 1-hydroxy-2-amino-4-nitro-6-propionylamino benzene are diazotized by following the procedure of Example 1. The suspension of diazo-compound is neutralized with Na_2CO_3 and is introduced at 0° C. into a solution of 14.9 parts of 2-hydroxy-5,6,7,8-tetrahydronaphthalene in 40 parts of water, 4 parts of NaOH and 50 parts by volume of pyridine.

The coupling occurs very quickly. The dye product obtained after coupling contains about 30% by volume of pyridine.

The dye, which is isolated and dried, is a brown powder having the following formula:

This dye possesses shade and properties similar to the dye of Example 1.

Example 3

20 parts of 1-hydroxy-2-amino-4-chloro-6-acetamino benzene are diazotized and coupled as in Example 1.

A monoazo dye having the following formula:

is obtained in the form of a dark-brown powder which dyes wool using the metachrome process. A brown shade, clearer than that of the preceding example, having a violet tint and good wet and light fastness, is obtained.

This dye is also suitable for dyeing followed by successive chromation.

Examples 4-7

5 These examples are conducted by following the procedure of Example 1. In each case, 2-hydroxy-5,6,7,8-tetrahydronaphthalene is used as the coupling component. The various other dye components employed and the results obtained are reported in Table I, shown below.

TABLE I

Ex. No.	Diazotized base coupled with 2-hydroxy-4, 5, 6, 7-tetrahydronaphthalene	Color shade after chromation and characteristics with respect to the dye of Ex. 1.
15		
4	1-hydroxy-2-amino-4-nitro-6-formylamino benzene.	Substantially the same shade of brown; slightly lower light fastness.
20	1-hydroxy-2-amino-4-nitro-6-chloroacetamino benzene.	Brown with a violet tint.
6	1-hydroxy-2-amino-4-nitro-6-methoxycarbonylamino benzene.	Almost equal shade; slightly lower light fastness.
25	1-hydroxy-2-amino-4-chloro-6-propionylamino benzene.	Brown with a violet tint; better fastness to fuling.

Many variations and modifications can, of course, be made without departing from the spirit and scope of the present invention.

Having thus described the present invention, what it is desired to secure and claim by Letters Patent is:

1. A monoazo dye having the formula

45 wherein "X" is selected from the group consisting of chlorine, and a NO_2 group, and "Y" is selected from the group consisting of a carboxylamino radical containing from 1 to 4 carbon atoms, a carboxylamino radical containing from 1 to 4 carbon atoms and further containing chlorine in the hydrocarbon chain, and an alkoxy-carboxylamino radical containing from 1 to 4 carbon atoms.

50 2. The monoazo dye of claim 1 wherein "X" is a chlorine atom.

3. The monoazo dye of claim 1 wherein "X" is a NO_2 group.

4. The monoazo dye of claim 1 wherein "Y" is a carboxylamino radical containing from 1 to 4 carbon atoms.

5. The monoazo dye of claim 1 wherein "Y" is a carboxylamino radical containing from 1 to 4 carbon atoms and further containing chlorine in the hydrocarbon chain.

60 6. The monoazo dye of claim 1 wherein "Y" is an alkoxy-carboxylamino radical containing from 1 to 4 carbon atoms.

65 7. The monoazo dye which has the formula:

5

8. The monoazo dye which has the formula:

9. The monoazo dye which has the formula:

10. The monoazo dye which has the formula:

11. The monoazo dye which has the formula:

6

12. The monoazo dye which has the formula:

5

10

13. The monoazo dye which has the formula:

15
